[57] CLAIM

The ornamental design for a lid for refuse container, substantially as shown and described.

DESCRIPTION

FIG. 1 is a perspective view of a lid for refuse container showing my new design.

FIG. 2 is a top plan view thereof.

FIG. 3 is a side elevational view on a slightly enlarged scale, taken along line 3—3 of FIG. 2, the side opposite being a mirror image thereof;

FIG. 4 is a side elevational view on a slightly enlarged scale, taken along line 4—4 of FIG. 2, the side opposite being a mirror image thereof;

FIG. 5 is a bottom plan view thereof.

FIG. 6 is a vertical sectional view on a slightly enlarged scale taken along line 6—6 of FIG. 2.

FIG. 7 is a vertical sectional view on a slightly enlarged scale taken along line 7—7 of FIG. 2.

FIG. 8 is a vertical view similar to FIG. 6 but shows the hinged sections of the lid pivoted to an open position.
